(57) CLAIM

The ornamental design for a “cargo bottle pack”, as shown.

DESCRIPTION

FIG. 1 is a front elevational view of our cargo bottle pack design;

FIG. 2 is a top plan view thereof;

FIG. 3 is a rear elevational view thereof;

FIG. 4 is a bottom plan view thereof;

FIG. 5 is a right side view thereof; and,

FIG. 6 is left side view thereof.

The broken line showing in FIGS. 1-6 of buckles and bottle form no part of the claimed design and are for illustrative purposes only.
